Primary Examiner — Vy N Koenig(74) *Attorney, Agent, or Firm* — Lerner, David, Littenberg, Krumholz & Mentlik, LLP**CLAIM**

The ornamental design for an image device holder, as shown and described.

DESCRIPTION

FIG. 1 is a front, top, and left perspective view of an image device holder according to the design;

FIG. 2 is a rear, top, and right perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The evenly spaced broken lines and the spaces therein are included for illustrating environmental aspects only and form no part of the claimed design. The unevenly dashed broken lines depict boundaries of the claim and form no part of the claimed design.
